UNITED STATES PATENT OFFICE.

EBENEZER A. W. JEFFERIES, OF WORCESTER, MASSACHUSETTS, ASSIGNOR TO JEFFERIES-NORTON CORPORATION, OF WORCESTER, MASSACHUSETTS, A CORPORATION OF DELAWARE.

REFRIGERATING APPARATUS.

1,379,102.

Specification of Letters Patent. Patented May 24, 1921.

Original application filed January 26, 1915, Serial No. 4,536. Divided and this application filed January 21, 1918. Serial No. 212,862.

To all whom it may concern:

Be it known that I, EBENEZER A. W. JEFFERIES, a citizen of the United States, residing at Worcester, in the county of 5 Worcester and Commonwealth of Massachusetts, have invented new and useful Improvements in Refrigerating Apparatus, of which the following, taken in connection with the accompanying drawings, is a specification.

The present application is a division of my prior application for a "Process of refrigeration," Serial No. 4,536, filed January 26, 1915, and issued as U. S. Letters Patent 15 No. 1,264,807, dated April 30, 1918. The present invention, in common with that of my above designated patent, relates in general to the art of refrigeration, and has particular reference to the attainment of extremely low 20 temperatures by the use of a gaseous working fluid. The low temperatures thus attained may be used, if desired, in securing extreme refrigerative effects; or the invention may be utilized for the purpose of liquefying, in whole or in part, the gaseous working fluid, and if desired this liquefaction, if the gas be a mixed gas, may be employed in connection with suitable distillation agencies to effect the separation of the 25 gas into its constituent elements. Moreover, as will be shown, the invention may with advantage be used for the cheap and efficient production of power in a form available for the production of useful work.

The present invention is chiefly concerned 35 with the recovery of power from the gases which are liquefied, as described in my aforesaid patent. The power thus recovered may be utilized in driving or assisting 40 in driving the devices which are used for the initial compression of the gas, whereby a marked increase in efficiency and fuel economy, over other systems of this character now in use, is attained. Other objects 45 and advantages will appear from the following description of the invention, reference being had in this connection to the

accompanying drawings, wherein the single figure is a diagrammatic representation of one arrangement of apparatus in accordance with the invention, for carrying out the process described in my aforesaid patent. It is to be understood, however, that my invention is not in any way confined to the herein described, or any other particular arrangement of apparatus, nor to the herein described methods of operating the same, except in so far as specified in the annexed claims; the drawings and description being illustrative merely of one way 50 of utilizing the broadly new principles of the invention.

As heretofore practised, systems of this class involving the liquefaction of gases have been characterized by the release of 55 the condensed fluid from pressure, thereby permitting spontaneous reevaporation of said condensed fluid, with a resulting high refrigerative effect during such reevaporation. The present invention differs essentially from such prior systems, in that the condensed fluid instead of being released from pressure, is either placed under additional pressure or sufficient pressure is maintained upon it so that the gas subsequently 60 evaporated therefrom possesses the capability of absorbing heat usefully, thereby acquiring considerably more than enough energy, when properly applied, to counterbalance the diminished refrigerative effect during 65 reevaporation.

The application of this principle for the attainment of the objects hereinbefore mentioned is illustrated by way of example in the apparatus of the accompanying drawing, wherein is shown, diagrammatically, a compressor 1, for compressing the gas as a preliminary to its liquefaction, as herein-after described. The compressed gas is cooled by any suitable cooling device 2, as 70 for instance a water cooler, which extracts the heat of compression therefrom. From the cooling device 2 the gas is led to a passage 3 of a heat interchanger, the latter

being designated as a whole by the numeral 4. At the cold end of said heat interchanger the passage 3 terminates in a receptacle 5, which serves as a container for 5 the gas after its liquefaction by the action of the interchanger. There is no escape for the liquid from the container 5 to the return circuit of the system except through a pump 6, which delivers the liquid into said 10 return circuit through a refrigerating coil 7, at a pressure higher than the pressure in the passage 3, it being understood that in common with other refrigeration systems of this class, my invention contemplates the 15 continuous liquefaction of the cooled compressed gas while traversing the passage 3 of the heat exchanger 4, to replenish the supply of liquid in the container 5, as fast as the same is pumped out.

20 The fluid leaving the coil 7 enters a passage 8 forming another part of said heat exchanger 4, wherein it is evaporated and has its temperature raised by interchange of heat with the gas in the passage 3 coming in 25 from the compressor 1. The pressure prevailing in passage 8 and coil 7 is obviously due to the resistance imposed against outflow of vapor from the upper end of said passage; in forcing liquid into the coil 7, the 30 pump 6 must put it under sufficient pressure to overcome the pressure thus maintained in passage 8, which, as above stated, is higher than the pressure prevailing in passage 3. The heat exchange between the 35 fluids in passages 3 and 8, in a manner similar to that well-known in apparatus of this character, entails the discharge of high pressure fluid from the top or warm end of passage 8 at substantially the temperature of 40 the gas entering the interchanger at the top or warm end of passage 3; the substantial equalization of temperatures at any given level by heat interchange between the two passages 3 and 8, is contemplated, and in 45 common with other apparatus of this character, the temperatures are lower, the lower the level reached in said interchanger. The passage 8 communicates with a heating device 9, wherein the whole or a portion of the 50 gas evaporated from the liquid leaving the pump 6, has its temperature further increased, prior to its use in a hot expansion engine or motor 10, which may be operatively connected to drive the compressor 1.

55 Part of the gas passing through the exchanger in passage 3 may be used in a cold expansion or refrigerating engine 11, which may be operatively connected to the compressor 1 and motor 10. Said engine 11 exhausts into the cold end of a passage 12 which forms a third part of the heat exchanger 4. If preferred, that portion of the gas used in said refrigerating engine 11 may be taken from the passage 8, after reevaporation at the increased pressure, instead of

from the passage 3. The gases exhausted from said engine 11, together with the exhaust gas from the motor 10 may ultimately be returned to the inlet of the compressor through pipes 13 and 14, respectively, recompressed in said compressor, and passed again through the same circuit.

70 Assuming the establishment of the conditions illustrated in the figure, wherein the broken lines denote the presence of liquefied gas in container 5 and coil 7, it will be clear that the cold expansion engine 11, passage 12, and their several interconnections constitute an external cooling agency, the provision of which, in one form or another, is 75 requisite to the liquefaction of the gas traversing passage 3 from the compressor 1 to the container 5. As set forth above, the increase in pressure upon the liquid effected by the pump 6, imparts to the outgoing gas 80 evaporated from such liquid, the ability to absorb heat usefully and thus to attain more energy than is possessed by the same quantity of gas brought into the exchanger 4 at 85 the original pressure by passage 3.

90 The amount which the pressure is increased by pump 6 governs the amount of available energy contained in the gas leaving the exchanger on its way to the heater 9. The cold expansion engine 11 also contributes some energy, and the balance, to 95 make up the total required to operate the system, may be supplied, in part at least, by the addition of heat to the outgoing gas, at the increased pressure, in the heater 9, causing 100 the hot expansion motor 10 to deliver a large portion of the power required for operating the entire system.

105 It will be seen, therefore, that the invention contemplates an increase, rather than a decrease in the pressure of the liquefied gas; an evaporation of the same during its return through the exchanger under such increased pressure; the addition of heat to 110 said products of evaporation by external means, still further increasing its available energy over that absorbed in compressing the incoming gas; and the recovery of power therefrom to perform useful work. The heat required for vaporizing the liquid, so placed 115 under increased pressure, and for raising the temperature of the vapor in the exchanger is derived from an interchange of heat with the fluid which is passing through earlier stages in the process, and from heat leaking 120 into the exchanger from the atmosphere; the surplus heat required to raise the temperature of the said vapor above that of said incoming fluid, in order still further to increase the available energy contained in said 125 vapor over that absorbed in compression of said incoming fluid, is derived from exterior sources, such as steam, combustible fuel, or waste heat.

130 I am aware that the system herein de-

scribed can be most usefully employed only with fluids whose boiling points are below ordinary atmospheric temperatures, that is, with fluids which are gaseous in their free state. I am further aware that raising the pressure of the liquefied fluid before evaporation works a certain disadvantage by reducing its latent heat of vaporization, and in consequence, decreasing the refrigerative power of a given quantity of such fluid. But I find that such disadvantage is not only completely compensated for, but is considerably outweighed or overbalanced in economic result, by the advantage herein set forth, namely, the recovery of power, capable of being applied, if desired, to the production of additional refrigeration and to operating the system in a more efficient manner than heretofore.

Although I have described the invention as involving an increase on the pressure on the liquefied fluid before reëvaporation for the purpose of ultimate power economy, yet it will be obvious that the same purpose may be accomplished, in less degree, if the pressure is merely sustained instead of being released in the usual manner; or, the pressure may even be reduced and still carry out the purpose of this invention by retaining sufficient pressure to permit of absorbing heat usefully for the production or recovery of power.

It is to be understood that the invention, as herein described, does not of necessity entail either the complete or the absolute liquefaction of the gaseous working fluid, and that the terms "liquefaction," "liquid" and "liquefied" as used herein and in the appended claims apply as well to a condition of the fluid where in density and temperature it substantially approaches the liquid state. In such a condition said fluid is susceptible to a pressure increase by the expenditure of an almost negligible amount of power, which, together with the power required for initial compression is largely recoverable in the efficient manner hereinbefore set forth.

In the application of the foregoing new principles, which differ radically and essentially from the principles underlying previous systems of this class, it is to be understood that my invention is in no sense limited to equivalents of the apparatus shown, said showing being wholly diagrammatic and illustrative and adopted solely for the purpose of simplifying the explanation of said broadly new principles.

I claim:

1. The combination with means for liquefying a working fluid which is gaseous in its free state, of means for sustaining the pressure on the evaporate from said liquid, means for circulating said evaporate in heat exchanging relation to the gaseous fluid

about to undergo liquefaction, and means for thereafter expanding said evaporate, to furnish power.

2. In a system of the character described, means for liquefying a gaseous working fluid, comprising a reverse flow interchanger, and means for sustaining the pressure of the fluid in the outgoing side of said interchanger.

3. In a system of the character described, means for liquefying a gaseous working fluid, comprising a reverse flow interchanger, means for sustaining the pressure of the fluid in the outgoing side of said interchanger and a motor for the expansion of the said outgoing fluid under pressure, to produce useful work.

4. In a system of the character described, means for liquefying a gaseous working fluid, comprising a reverse flow interchanger, means for sustaining the pressure of the fluid in the outgoing side of said interchanger means for heating the evaporate of said outgoing fluid under pressure, and a motor for the expansion of said heated evaporate.

5. The combination with means for liquefying a working fluid which is gaseous in its free state, of means for increasing the pressure on the evaporate from said liquid, means for circulating said evaporate in heat exchanging relation to the gaseous fluid about to undergo liquefaction, and means for thereafter expanding said evaporate, to furnish power.

6. In apparatus of the character described, the combination with means for progressively liquefying a gaseous working fluid, of means for sustaining or increasing the pressure on the liquefied portion of said fluid, and means for maintaining said pressure on the evaporate from said liquefied portion during its circulation, in heat exchanging relation to the gaseous fluid about to undergo liquefaction.

7. In apparatus of the character described, the combination with means for progressively liquefying a gaseous working fluid, of means for sustaining or increasing the pressure on the liquefied portion of said fluid, and means for circulating the evaporate from said liquefied portion, under said pressure, in heat exchanging relation to the gaseous working fluid which is about to undergo liquefaction.

8. In apparatus of the character described, the combination with means for progressively liquefying a gaseous working fluid, of means for maintaining an increased pressure on the evaporate from the liquefied portion, means for circulating said evaporate in heat exchanging relation to the gaseous working fluid about to undergo liquefaction, means for supplying external heat to said evaporate, and means for

expanding said heated evaporate, to furnish power.

9. In apparatus of the character set forth, the combination with a reverse flow heat interchanger, of refrigerating means for promoting the liquefaction of a gaseous working fluid in the cold end of said interchanger, and means for maintaining a

sufficient pressure upon the fluid in the liquid state, to enable the evaporate therefrom to absorb external heat usefully. 10

Dated this 17th day of January, 1918.
